C. S. BURTON.
CONTAINER FOR MUSIC ROLLS AND THE LIKE.
APPLICATION FILED SEPT. 15, 1919.

1,399,541.

Patented Dec. 6, 1921.

Inventor:
Charles S. Burton,

Witness:

John H. Burton

By Burton Burton
His Atty.

UNITED STATES PATENT OFFICE.

CHARLES S. BURTON, OF OAK PARK, ILLINOIS.

CONTAINER FOR MUSIC-ROLLS AND THE LIKE.

1,399,541.

Specification of Letters Patent.

Patented Dec. 6, 1921.

Application filed September 15, 1918. Serial No. 323,829.

To all whom it may concern:

Be it known that I, CHARLES S. BURTON, a citizen of the United States, and a resident of Oak Park, in the county of Cook and State 5 of Illinois, have invented certain new and useful Improvements in Containers for Music-Rolls and the like, of which the following is a specification, reference being had to the accompanying drawings, forming a part 10 thereof.

The purpose of this invention is to provide an improved container, particularly adapted for such articles as music rolls and the like, of which the containers are commonly 15 packed in piles or tiers with the ends only accessible, so that it is desirable to have the contents withdrawn through the end of the container. It consists in the elements and features of construction shown and described 20 as indicated in the claims.

In the drawings:

Figure 1 is a longitudinal vertical section of a container embodying this invention, the same being shown in closed position with a 25 roll therein.

Fig. 2 is a similar view showing the container closure withdrawn for protruding the end of the roll to permit its engagement by the hand for complete withdrawal.

30 Fig. 3 is a section at the line 3—3, on Fig. 2.

Fig. 4 is a section at the line, 4—4, on Fig. 2.

The container shown in the drawings comprises a tubular box, 1, having one end closed and the other end open, and having at the open end a closure hinged at one edge of the closure at one side of the end of the box for swinging to open and close the box. At the 40 closed end of the box there is mounted therein a spring, 3, preferably in the form of a conical coil or helical spring with its wider base at the end of the box and its smaller end positioned for encountering the end of the inserted music roll or spool, 4, as shown. This spring is of sufficient strength to impel the roll or spool, which may be thrust into the box and held therein when the closure at the open end is closed, outward so as to protrude the end of the roll when said closure is swung down to open position. For holding the closure, 2, in closed position for retaining the contents of the box therein, there is provided a spring device, 5, which is in the 50 form of a three-sided open parallelogram consisting of two side bars, 5^a, and a cross

bar, 5^b, connecting them. This device is made of spring wire and has the two free ends of the side bar anchored in blocks, 6, 6, which are glued into the corners of the box, 60 the wire being bent to extend obliquely upward from said blocks, the cross bar extending across in front of the closure, 2, when the latter is at closed position, and adapted to swing down so as to stand or lie substantially 65 in the plane of the bottom side of the box, to permit the closure to swing to open position, that is, substantially to horizontal position in the plane of the bottom of the box. The operator desiring to withdraw the roll 70 from the box will press down the cross bar of the spring catch device, 5, to horizontal position, whereupon the spring, 3, reacting will thrust the roll outward over the depressed or horizontal closure, and will thereby lock said closure against returning to closed position until the operator, taking hold of the protruded end of the roll, completes the withdrawal, whereupon the closure will be swung back by the spring catch 80 device into closed position. For convenience in opening the box to re-insert the roll the closure, 2, has a finger notch, 2^a, at the upper edge, at which the operator will engage the closure to swing it down to horizontal position for inserting the roll into 85 the box.

To prevent the closure from being forced inward when the box is empty, beyond convenient reach for engaging its aperture 2^a, to withdraw it, it is made of greater width transversely,—that is, vertically,—than the corresponding interior dimension of the box; and the hinged edge is set inward from the forward open end of the box as shown in 95 Fig. 1. This relation of the vertical dimension of the closure to the vertical interior dimension of the box, and the position of the hinge, constitutes the preferred means for stopping the closure at its closed position. 100

I claim:

1. A container comprising a tubular box having an open end, and a closure hinged at one edge of the open end for swinging from closed to open position; a spring in the rear 105 closed end of the box for ejecting the contents through the open end, and a hinged latch carried by the box extending in front of the closure for holding it at closed position and which is accessible for swinging it 110 away from closure-holding position; whereby when the latch is thus moved, the spring

thrusts the contents against the closure and opens the same, protruding the contents from the box, the latch being mounted for movement past the hinged edge of the closure for releasing the latter.

2. In a structure defined in claim 1, the latch being spring-held in closure-locking position, to be moved past the hinged edge of the closure for releasing the closure.

10 3. In the construction defined in claim 1, the latch comprising side arms and a cross bar, the side arms extending along the two opposite sides of the box between which is the side at which the closure is hinged, and 15 a cross bar extending across in front of the closure at closed position.

4. In the structure defined in claim 1, the closure being hinged at a short distance back of the open end of the box and being adapted to swing into the box in closing.

20 5. In the structure defined in claim 1, the edge of the closure opposite its hinged edge having a finger-engaging recess or notch.

6. In the construction defined in claim 1, foregoing, the closure being adapted to 25 swing into the box in closing, and means for stopping its inward movement at normally closed position, independently of the contents of the box.

7. In the construction defined in claim 1, 30 foregoing, the closure being hinged at its edge back of the open end of the box and adapted to swing into the box in closing and having its dimension transversely to the edge at which it is hinged greater than the 35 corresponding dimension of the box; whereby the closure is stopped at the opposite edge against the inner side of the box with freedom for being opened outwardly by the expelled contents of the box upon release of the latch.

In testimony whereof, I have hereunto set my hand at Chicago, Illinois, this 12th day of September, 1919.

CHARLES S. BURTON.
